UNITED STATES PATENT OFFICE.

SEYMOUR VAN NOSTRAND, OF STORMVILLE, NEW YORK.

VEHICLE-SPRING.

SPECIFICATION forming part of Letters Patent No. 236,281, dated January 4, 1881.

Application filed August 4, 1880. (No model.)

To all whom it may concern:

Be it known that I, SEYMOUR VAN NOSTRAND, of Stormville, in the county of Dutchess and State of New York, have invented a new and Improved Vehicle-Spring, of which the following is a specification.

The object of this invention is to provide an adjustable vehicle-spring of superior elasticity and strength, whose elasticity can readily be increased or diminished at will.

Figure 1 is a plan of the spring attached to the side bars of a wagon. Fig. 2 is a transverse section on line x x , Fig. 1. Fig. 3 is an enlarged side elevation of a clip holding the end of a transverse spring to a side spring of the vehicle-spring. Fig. 4 is an enlarged end elevation of the same. Fig. 5 is an enlarged side elevation of a clip and coupling securing the end of a side spring to a side bar of a wagon. Fig. 6 is an enlarged end elevation of the same. Fig. 7 is an enlarged plan of the coupling.

Similar letters of reference indicate corresponding parts.

In the drawings, A A represent the side bars of a vehicle, and B B the connected end bars thereof.

C is the spring, the ends k k of whose side springs, C' C', are rigidly secured on the under side of the side bars, A A, by means of the clips and couplings D E.

The clips D straddle the side bars, A A, and have their ends entered into the holes a a of the couplings E E, and the couplings E E are secured on said clips D D by the nuts b b , that are screwed on the ends of said clips D D.

The ends of the side springs, C' C', are entered between the depending lugs d d of the

couplings E, and are there firmly held on the pins or bolts c c , that pass through said lugs d d , 40 parallel with the side bars, A A, and through the end eyes, f f , of the said springs C' C'.

The transverse or cross springs, G G, of the spring C cross from one to the other of the side springs, C' C', beneath the same, forming 45 the H-shaped spring C, and have their ends connected to the said springs C' C' by the clips F F, that straddle said springs C' C', and have their ends entered through the said springs G G and secured by nuts g g . This 50 spring C offers not only an elastic support to the vehicle-body that is designed to be placed upon the cross-springs G G, but also a torsional or twisting resistance thereto, because of the downward-inclined curve of the ends of 55 the side springs, C' C'. The springs G G are connected with the side springs, C' C', in such a manner that the former may be moved nearer to each other than herein shown, to increase the elasticity of the spring C, by bringing the 60 bearing-point of the vehicle-body nearer the center thereof; or said springs G G may be moved apart to increase the stiffness of said 65 spring C.

Having thus described my invention, what 65 I claim as new, and desire to secure by Letters Patent, is—

The H-shaped spring C, consisting of the sides C' C' and cross-pieces G G, the former having bent ends k , downwardly inclined, to 70 adapt the spring to be applied, as shown and described.

SEYMOUR VAN NOSTRAND.
